UNITED STATES PATENT OFFICE.

FRANK W. DILKS, OF PHILADELPHIA, PENNSYLVANIA, AND DAVID REYAM AND EUGENE E. DU PONT, OF WILMINGTON, DELAWARE, ASSIGNORS TO THE INTERNATIONAL RADIATOR COMPANY, OF WILMINGTON, DELAWARE, A CORPORATION OF DELAWARE.

RADIATOR.

1,008,707.

Specification of Letters Patent. Patented Nov. 14, 1911.

Application filed September 6, 1910. Serial No. 580,706.

To all whom it may concern:

Be it known that we, FRANK W. DILKS, a citizen of the United States, residing in the city and county of Philadelphia, State of Pennsylvania, and DAVID REYAM and EUGENE E. DU PONT, both citizens of the United States, residing in the city of Wilmington, county of Newcastle, State of Delaware, have invented a new and useful Radiator, of which the following is a description.

Our invention consists of an apparatus for radiating the heat of heated air from a furnace or similar air-heater.

It further consists of an apparatus for radiating such heat and returning the air to the furnace to again be heated after it has given off its heat in the radiator.

It further consists of such apparatus in which large radiating surfaces are provided, while the apparatus occupies a proportionately small space.

It further consists of improved joints for connecting the radiator sections or units.

It further consists of an improved joint for connecting the radiator units to the wall box or terminal of the hot air flue.

It further consists of other novel features of construction, all as will be hereinafter fully set forth.

For the purpose of explaining our invention, the accompanying drawing illustrates a satisfactory reduction of the same to practice, but the important instrumentalities thereof may be varied, and so it is to be understood that the invention is not limited to the specific arrangement and organization shown and described.

Figure 1 represents a vertical section through our improved radiator. Fig. 2 represents a vertical section, in a plane at right angles to that of Fig. 1, of one of the radiator units. Fig. 3 represents a horizontal section of the radiator and wall boxes. Fig. 4 represents a face view of a wall box. Fig. 5 represents a view of the lower end of one of the units. Fig. 6 represents a vertical section of the lower end of a radiator unit and a wall box. Fig. 7 represents perspective views of parts of the joint between the radiator units. Fig. 8 represents a perspective detail view of a portion of the front of a wall box. Fig. 9 represents a vertical section of a form of radiator constructed to allow the air to discharge into the surround-

ing air. Fig. 10 represents an elevation of the last unit of said form of apparatus, showing the register opening in the same.

Similar numerals of reference indicate corresponding parts in the figures.

Referring to the drawings:—the radiator is composed of units 1, made from sheet metal and each consisting of two halves, preferably from stamped or otherwise shaped metal sheets, having interlocking beaded edges. The edges of one half are formed with a bead 2, semicircular in cross section, and the edges of the other half are formed with a bead 3, circular in cross section, which latter bead encircles the semicircular bead, and thus forms a firm and tight joint at the seams uniting the halves of each unit. The units are deep and narrow and oblong in cross section, and at the lower ends they are formed with necks 4, projecting from one edge of each unit, and also oblong in cross section. Near its upper end, each unit, excepting the terminal or end units of each set, has a laterally projecting neck 5, on each flat side, and one of said necks has an inturned flange 6, formed with an annular groove 7 in its face, which preferably is interrupted to form an annular series of segmental grooves. The opposite neck of the adjacent section has a corresponding annular rib 8 upon its face, which is also preferably interrupted to form an annular series of segmental ribs, registering with and engaging the grooves of the opposed neck, said series of ribs and grooves engaging to insure tight joints and perfect alinement of the units. The unit at the end of each set has only one of said necks, illustrated in the drawings, as the neck having the annular grooves at one end unit and the neck having the ribs at the other end unit. The necks, flanges and ribs and grooves are stamped or otherwise shaped from and integral with the unit-halves and so produced in the process of shaping the latter. A wall box or casing 9 is provided to communicate with the opening of a furnace flue (not shown), and said box has a number of oblong openings 10, corresponding in shape to that of the lower necks 4 of the units. Each opening has an outwardly projecting flange 11, surrounding the lower portion of the same, and an inwardly projecting flange 12, surrounding the upper portion of the

- opening, and said flanges close the joint between the neck of each unit and the opening into which it is fitted. In fitting the neck of a section, the neck is placed from above 5 into the lower flange and is then moved into the opening, where the flanges will thus close the joint and prevent lateral escape of hot air through the same. Between two sets of units, connected to two wall boxes, are 10 placed two intermediate or center units 13, similar to the outer units, but each having only one joint neck 5, at its upper end to connect it to the adjoining unit, and both being connected near their lower ends by 15 necks 14, having annular interlocking groove and rib connections 15, like the joint necks 5. The lower ends of the two sets of units are spaced by collars 16, and the upper ends of the two center units are spaced 20 by a collar 17. The units are all connected near their upper and lower ends by means of stay-rods 18 and 19.
- The wall boxes 9 form respectively a supply box, and a return box, being respectively 25 connected to a flue conveying hot air from the furnace and a flue conveying air back to the air chamber of the furnace, (such flues not being shown), and each box has one set of units secured to it, four units being 30 illustrated in the drawings as forming a set, one set for the ascending hot air, and one set for the descending cooled air. The ascending hot air passes up through the units and passes from the upper ends of the same 35 through the connecting necks into the upper end of a center unit, through which it descends and passes into the second center unit and ascends through the same. From the upper end of said unit the air passes 40 through the connecting necks of the second set of radiator units and down through the latter to the wall box and flue carrying the now cooled air back to the heating chamber of the furnace. The air passing up and 45 down through the radiator gives off its heat through the units, which, on account of their deep and narrow shape, offer an extensive radiating surface while occupying comparatively small floor space.
- 50 In the above described form of radiator, heating is accomplished by radiation from the furnace heated air, without the latter entering the room, and thus impoverishing and vitiating the air in the same, and the 55 radiator may be employed with any hot air furnace, it being only necessary to provide return flues and connecting them with the bottom of the heating chamber of the furnace.
- 60 Conditions may arise when it is not practical or desirable to provide return flues, while it is desired to accomplish heating by radiation, and in such case the form illustrated in Figs. 9 and 10 is employed. In 65 this form the radiator units connected to

the wall box upon the return flue is dispensed with, and an annular series of register openings 20 is provided at the upper end of the unit carrying the ascending air, with an annular register plate 21, covering the same, so that the hot air, after having radiated heat in its passage through the radiator units, may be admitted to the room under control of the register.

In either form, the heat from the furnace heated air is utilized by radiation. In the form having return to the furnace, the air in the room is only heated by radiation, and in the form illustrated in Figs. 9 and 10, the air in the room is heated partly by radiation, and partly by direct admission of warm air. The heated air is retarded in its passage through the radiator so as to part with a considerable portion of its heat by rising in the ascent set of units, thereupon 75 descending through the single descent unit, again ascending through the single ascent unit, and finally descending through the descent set of units. By passing the heated air tortuously through the deep and narrow 80 units, comparatively large radiating surfaces are provided, through which the heat from the thin and flat sheets or streams of heated air may be communicated to the surrounding air and a proportionally large 85 amount of heat given out from such thin sheets or streams. The intermediate or center units serve as reversing units, reversing the ascending columns of hot air to descend the descent units.

Having thus described our invention what we claim as new and desire to secure by Letters Patent, is:—

1. In a radiator, a set of ascent radiator units arranged side by side and having inlet at their lower ends, and connected at their upper ends to communicate with each other, a set of descent radiator units arranged side by side and having outlet at their lower ends and connected at their upper ends to communicate with each other, and a pair of intermediate reversing units connected at their lower ends and respectively connected to the upper end of one unit of a set.
2. In a radiator, a set of narrow and deep, vertical radiator ascent units arranged side by side and having inlet at their lower ends and connected at their upper ends to communicate with each other, a set of narrow and deep, vertical radiator descent units arranged side by side and having outlets at their lower ends and connected at their upper ends to communicate with each other, and a pair of narrow and deep intermediate reversing units each connected at its upper end to the upper end of one unit of a set and connected with each other at their lower ends.
3. In a radiator of the character stated, a supply wall box and a return wall box,

- a set of vertical ascent radiator units arranged side by side and connected at their lower ends to the supply box and connected together at their upper ends to communicate with each other, a set of vertical descent radiator units arranged side by side and connected at their lower ends to the return box and connected together at their upper ends to communicate with each other, 5 and a pair of intermediate reversing units connected at their upper ends, each to one set of units to communicate with the same, and at their lower ends to communicate with each other.
- 10 4. In a radiator, a wall box having an oblong opening formed with an outwardly projecting flange around the lower portion of its periphery, and an inwardly projecting flange around the upper portion of its periphery, and a radiator unit formed with a neck fitting into said opening and flanges.
- 15 5. In a hot air radiator, a supply wall box having oblong flanged openings in its face, a return wall box having oblong flanged openings in its face, two sets of deep and narrow, vertical sheet metal radiator units formed with laterally extending necks, oblong in cross section and entering said openings, and the units of each set formed with joined necks at their upper ends connecting each set of units, and a pair of deep and narrow, vertical reversing units connected by joined necks at their lower ends, and each connected at its upper end by a joined neck to the upper end of the adjoining unit of one set. 20 30 35
